UNITED STATES PATENT OFFICE.

HANS RIES, OF MUNICH, GERMANY.

CAR FOR QUENCHING COKE.

1,006,281.

Specification of Letters Patent. Patented Oct. 17, 1911.

Application filed February 13, 1909. Serial No. 477,550.

To all whom it may concern:

Be it known that I, HANS RIES, a subject of the Emperor of Germany, and resident of Munich, Bavaria, Germany, have invented certain new and useful Improvements in Cars for Quenching Coke, of which the following is a specification.

My invention relates to a car adapted for use in conjunction with retorts or gasifying chambers in which coke is produced.

My improved car comprises a quenching trough adapted to receive the coke as it is discharged from the retort or furnace and a quenching and conveying channel to which the partly quenched coke is transferred from said quenching trough and in which such coke is quenched completely, to be finally discharged into a pit or the like.

The invention also contemplates the division or spreading of the coke as it passes into the quenching trough to facilitate the quenching action and also devices for regulating the amount of partly quenched coke passing from the trough to the conveyer.

25 The traveling motion of the car, the operation of the conveyer and the actuation of the doors closing the outlets of the retorts or furnace, are preferably accomplished by means of motors located upon the car.

30 In the accompanying drawings which illustrate an embodiment of my invention, Figures 1 and 1^a together represent a front elevation of the car with parts in section; Fig. 2 is a side elevation thereof with parts in section illustrating the coöperation of certain devices on the car with doors of the furnace, and Fig. 3 is a plan view of the car partly in section.

35 The frame 1 of the car is supported by suitable trucks having wheels 2 arranged to travel on rails 3 between which is located the pit 4, so that the car travels over the pit. Upon the car is located the quenching trough 5 in which the coke receives a partial quenching, and a channel 6 in which the quenching of the coke is completed as described hereinafter.

40 A suitable shell 7 is provided on the sides and on the top of the car. The steam which is formed in the trough 5 upon the quenching of the coke, escapes through a chimney or funnel 8.

The width of the quenching trough 5 corresponds to that of the furnace chamber or

retort 9, said trough being of rectangular shape, open at the top, and having hollow side walls 10 and 11 respectively adapted to contain water. The bottom of the quenching trough 5 is closed partly by a pivoted plate 12 and partly by a slide 13. This slide is provided with a rack 14 engaged by a pinion 15 which may be operated by turning a hand-wheel 16 thus moving the slide 13 up or down and regulating the size of the opening left between the plate 12 and the lower edge of the slide 13. By swinging the plate 12 to the right as indicated by dotted lines in Fig. 1, the coke instead of passing out from the quenching trough to the channel 6, may be discharged into a chute 17 and thus reach the pit 4 without further quenching. As a rule, however, the plate 12 is in the position indicated by full lines in Fig. 1 and the coke passes from the quenching trough 5 to a roller 18, which extends the full width of the channel 6 and is provided with bars 19 to engage and feed the coke. From this roller the coke passes to the conveyer 20 which carries the coke upward along the inclined channel 6 and finally drops the coke into the pit 4 through the outlet or spout 21. The frame 1 is provided with supports 22 carrying a reservoir 23 adapted to receive water from a stationary main 24 (see Fig. 2) with which said reservoir may be brought into registry. The reservoir 23 is connected by a pipe 25 with a larger reservoir 26 located upon the platform 27 of the car. From the bottom of the reservoir 26 a pipe 28 leads downward, passing through the side wall 29 of the car and then communicating with two pipes 30 located at a right angle to the pipe 28 and connected with spraying pipes 31 extending above the channel 6 and arranged to spray water on the coke traveling in said channel. The pipes 30 are also connected with the hollow wall 11 of the quenching trough, which like the wall 10 is provided at its upper portion with openings 32 for discharging jets of water. The two hollow walls 10 and 11 are connected by a pipe 33.

On the side which is toward the retort or chamber 9 the quenching trough 5 is provided with an incline 34 adapted to register with a chute 35 secured to the furnace. On the incline 34 is provided a wedge-shaped upright blade or ridge 36, which serves to di-

vide and distribute the coke as it passes from the furnace to the quenching trough, thereby increasing the efficiency of the quenching jets discharged through the openings 5

32. The partially quenched coke then passes out through the opening at the bottom of the trough 5, either direct to the chute 17, or in the general operation, to the roller 18 and the conveyer 20; in the latter case the coke 10 is further quenched by the jets discharged from the pipes 31, as indicated in Fig. 1.

The door 37 of the retort 9 is opened and closed by means of the motor 38 carried by the platform 27. The said door swings 15 about the axis 39 located at its upper end and is held in the closed position by a toothed wheel 40 engaging a rack bar 41 at the lower end of the door. When it is desired to open the door, the rack bar 41 is 20 first released from the pinion 40 by turning this pinion by means of the worm 42 in a direction contrary to that used in closing the door. The worm 42 is carried by a shaft 43, which may be rotated by means of the 25 clutch 44-45 from a shaft 46 carried by the car and driven from the motor 38 by means of gearing 47 and suitable connections.

The door 37 carries a bracket 83 pivoted at 82; the downward movement of said 30 bracket being limited by a stop 84, so that normally the bracket extends in a horizontal direction, or approximately so, as shown in Fig. 2. The forward end of the bracket 83 is adapted to be engaged by a hook 85 secured 35 to the chain 48 so that the hook may be raised or lowered, being preferably guided in a channel 86. The chain 48 passes over a sprocket 49 and has its free end secured to the frame of the car in such a manner that 40 it may follow the movement of the door in opening and closing it. The sprocket 49 is carried by a horizontal shaft 50 journaled in the supports 22. At one end of this shaft is secured a sprocket 51 driven by a chain 45 52 from a sprocket 53 on the shaft 54. This shaft is driven from the motor 38 by means of a reversing clutch of any suitable character, that is to say, the shaft 54 can be driven in one direction or the other. It will 50 be understood that by driving the shaft 54 in the proper direction the hook 85 will be raised thus pulling the door 37 into the open position indicated by dotted lines in Fig. 2.

The coke will then pass from the chamber 55 9 to the quenching trough 5 over the chute 35 and the incline 34. The motor 38 is also used to propel the car. For this purpose a sprocket 55, which may be driven by the motor, is connected by a chain 56 with a 60 sprocket 57 mounted on a shaft 58 in the lower part of the car. This shaft also carries pinions 59 engaging gear wheels 60 mounted on the axle 61 of one pair of wheels 2. In this manner the car may be caused

to travel in one direction or the other, such 65 movement being under the control of the motor 38, which may be operated by an attendant seated or standing on the car. The car may thus be brought into registry with the several retorts of a bench. 70

The conveyer chain 20 is preferably driven by a separate motor 63 located on the lower platform 62 of the car. This motor drives a train of gearing 64-65, the latter wheel being mounted on a shaft 66 which 75 also carries two pairs of sprockets 67-68. The sprockets 67 are connected by chains 69 with sprockets 70 on the shaft 71; the sprockets 68 are connected by chains 72 with sprockets 73 at the ends of the roller 18. 80 The conveyer 20 consists of several chains connected by cross bars (this being a well known construction) and is guided by sprockets 74 (see Fig. 3) and 75 at the upper and lower portions respectively of 85 the inclined channel 6. It will thus be seen that the roller 18 and the conveyer 20 are driven in unison and at a constant ratio relatively to each other. These parts should be operated at a relatively low speed. Above 90 the quenching trough 5 is arranged a folding door 76, made of two pivoted sections, which may be swung upward as indicated by the arrows in Fig. 1 so as to clear the opening above the quenching trough and 95 thus to allow the coke to pass from the chamber 9 to the quenching trough. To the shaft 50 is also secured a roller 77 on which is wound a rope 78, the lower end of which has secured to it a number of removable 100 weights 79 moving up and down in a cylinder 80. At the bottom of the cylinder is located a spring buffer 81. These weights 79 serve as a counterbalance for the door 37 so that its opening and closing may be effected easily. By the removal or addition of weights the proper amount of counterbalance is secured.

I claim as my invention:

1. A car for quenching coke, provided 110 with a quenching trough, a quenching channel and a discharge chute each in receiving relation to said trough, and means for directing the coke from the trough either to said chute or to the quenching channel. 115

2. In a coke quenching trough of the class described in combination, a quenching trough, oppositely arranged means for supplying a quenching medium, and an incline 120 for feeding coke into said trough, said incline being provided with a V shaped ridge directed oppositely to the direction of feed for dividing the coke supply and causing it to move toward said means for supplying quenching medium, substantially as and for 125 the purpose described.

3. In a coke quenching trough of the class described in combination, a quenching

trough having hollow walls provided with laterally arranged perforations, means for supplying a quenching medium to said hollow walls, and an incline at an end of said trough for feeding coke thereto said incline being provided with a V shaped ridge directed oppositely to the direction of feed for dividing the coke supply and causing it to move toward said lateral perforations,

substantially as and for the purpose described.

In testimony whereof I have hereunto set my hand in the presence of two subscribing witnesses.

HANS RIES.
